GRAVE SET

Robert Y. Wolfe, Rock Hill, S. C.

Application December 27, 1943, Serial No. 515,793

1 Claim. (Cl. 27—26)

This invention relates to a grave set which is easily transported to the burial ground and eliminates the necessity of using the complicated heavy and bulky grave sets and gives a beautiful grave at a greatly reduced cost, and eliminates all mechanical devices if desired, such as casket placers, and lowering devices. In using the grave set, it is preferable to use the casket box or vault as a support and to eliminate the necessity of using a lowering device and placer set as the use of same usually takes two or more trips in a truck to carry the full grave equipment, the box or vault, the placer and lowering device, the grass set, the chairs, and grave tent, and it takes two men to set a grave using all of this heavy equipment on account of the weight of same and its bulk. After the funeral service, it takes a truck to carry the old type of equipment back to the funeral home. By the use of my improved drape cover grave set, it takes only one trip to the cemetery with the truck, and that is to carry the casket box or vault and tent, and after the service is over at the grave, the drape cover grave set can be put in the hearse or a passenger car and carried back to the funeral home. One important advantage of this grave set is that it eliminates added expense in conducting a funeral at a great distance from the home of the deceased. Usually it is necessary for a funeral director who is transporting a body to a distant point for burial to engage the services of a local funeral home costing a great proportion of the profit arising from such services to furnish the grave set at the point of burial. By using the drape cover grave set, the funeral director need not hire another funeral home to set the grave, nor is it necessary for him to send his truck, for the present grave cover set will fit nicely in his hearse, and he not only saves the expense, but also saves fuel and tires and extra help by the use of this improved grave set.

It is therefore an object of this invention to provide a grave set preferably made in two sections and adapted to be joined together and fitted over the top of a casket box or placed on a grave vault bottom or grave vault depending upon the type of grave vault used, and having drapery thereon which covers lowering devices or supporting devices for the casket box and supports the casket on top of the grave set which is supported by the casket box or the vault bottom.

It is another object of this invention to provide a grave set comprising a casket support made in two sections and covered with suitable

drapery, and adapted to be slid endwise over the casket box to support the casket at the funeral service, and having draperies extending downwardly therefrom which entirely cover the grave, and lowering devices if such are used; furthermore, when the grave service is over, the casket can be slightly lifted and an attendant at each end of the grave set can remove the two sections of the grave set from beneath the casket, 10 and the casket is then lowered into the casket box ready for lowering into the grave.

Some of the objects of the invention having been stated, other objects will appear as the description proceeds, when taken in connection with the accompanying drawings, in which—

Figure 1 is an isometric view of the grave set in position over a casket box;

Figure 2 is a top plan view of the grave set, omitting the draperies;

Figure 3 is a side elevation of the grave set looking from the lower side of Figure 2, omitting the draperies;

Figure 4 is a cross-sectional view taken along the line 4—4 in Figure 2, showing the fabric removed from the end of the section, and in cross section, and omitting the rollers, their brackets, and the vertically disposed rollers on top of the section 10;

Figure 5 is a vertical sectional view taken along one end of the grave and showing the end of the casket box and the grave set and casket in elevation;

Figure 6 is a view similar to Figure 5, but showing the apparatus being used with a lowering device, and employing a vault bottom instead of a casket box for supporting the grave set and the casket disposed thereon.

Referring more specifically to the drawings, the numerals 10 and 11 indicate the two sections 40 of the top board or plane surface of the grave set. These sections 10 and 11 can be of any suitable material such as wood, ply-wood, aluminum, plastic material, or any other suitable light weight material.

To the bottom of section 11 is secured by any suitable means such as screws 12, elongated strips 13 and 14 and to the bottom of the section 10 are secured elongated strips 15 and 16. The strips 15 and 16 have secured on their lower surfaces on the end joining the section 11 channel iron members 17 and 18 and the strips 13 and 14 have secured thereon strap members 19 and 20 which project into the space between the channel members 17 and 18 and the strips 15 and 16 when the two sections 10 and 11 are in assembled position.

The structure shown in Figures 2, 3, and 4 eliminates the drapery, which is clearly shown in Figures 1, 5, and 6, except that in Figures 5 and 6, the end drapery is omitted.

The section 10 has its top covered with suitable drapery material 25, and on top of this drapery material, there are mounted strap iron members 26, 27, and 28 having a plurality of holes 29 therein in which vertically disposed pins 30 are disposed, each of the pins having a roller 31 thereon. These pins and rollers are adjustable in various holes 29 to correspond to the length and width of the casket being employed. Also mounted on top of the fabric covering section 10 is a pair of brackets 32 and 33 having each a roller 34 and 35 therein for supporting one end of a casket.

The section 11 likewise has brackets 36, 37, and 38 secured to the section 11, these brackets fitting on top of the fabric or drapery material 25 covering the top of the section 11, and having rollers 40, 41, and 42 therein for supporting the other end of the casket on the grave set. The sides and ends of the sections 10 and 11 have suitable drapery material 45 secured thereto which hangs in folds or pleats downwardly any desired distance to rest on the ground outside the periphery of the grave.

This apparatus can be employed by using a conventional lowering device having straps extending across the grave, but it is preferable to employ it without the lowering device, and in such instance, a pair of rigid iron members 46 and 47 are employed near each end of the grave which dip downwardly and have a transverse horizontal portion extending across the grave which supports the casket preferably with its bottom from six to ten inches below the top of the grave. Suitable straps 49 can be placed near each end of the casket, so that when the funeral service is over, and it is desired to lower the casket into the grave, the attendants can lift the casket, and one attendant at each end can pull the sections 10 and 11 apart from each other and remove them from the top of the casket box 50 which is supported on top of the members 46 and 47, then the casket is lowered into the box and the lid is secured in position, and then the casket box with the casket therein is lifted slightly and the iron members 46 and 47 are moved out to each end of the casket box and removed from the grave, and then the casket box with its casket therein can be lowered to the bottom of the grave. Of course, if a lowering device is used instead of the iron members 46 and 47, the lowering device would be operated to lower the casket box into the grave 66.

The members 13, 14, 15, and 16 not only serve to impart rigidity and strength to the sections 10 and 11, but they are also adapted to fit immediately inside the upper edges of the casket box 50 and to prevent sidewise and endwise motion of the grave set relative to the casket box. Of course, casket boxes vary in size and these members 13 to 16 are so positioned beneath the sections 10 and 11 as to fit the conventional size of the casket box, and of course, when a large casket box is used, these strips 13 to 16 inclusive would be disposed some distance away from the sides and ends of the casket box, but would still prevent any great movement of the grave set relative to the casket box.

In Figure 6, it is shown how the grave set could be used with a lowering device, and also how it could be used when a vault is employed instead of

a casket box. Here there are shown rods 60 and 61 disposed along each side of the grave, these being the conventional rods or tubes of a conventional lowering device, and as is well known in the art, these rods or tubes 60 and 61 have suitable canvas straps 62 extending from one to the other for supporting the casket or vault bottom or casket box thereon. It is evident that this type of lowering device could be used for supporting the conventional casket box 50, or it can be used for supporting the bottom 65 of a vault, and this vault bottom would support the grave set comprising sections 10 and 11 and associated parts, and the casket would be placed on top of the grave set comprising sections 10 and 11, and like reference characters will apply to the grave set as shown in Figure 6 as appearing in the other figures of the drawings.

It is thus seen that by the use of this grave set, the same can be taken apart and the two sections can have the sides and end draperies folded up onto the top portion and a suitable cover or wrapping placed around the same to protect the draperies, and these two sections can easily fit into a hearse and by use of the supporting members 46 and 47, an expensive and bundlesome lowering device does not have to be used, although it is quite evident that the apparatus can be used as well with a lowering mechanism as with the supports 46 and 47. One advantage of this grave set is that its two sections can be stored in a hearse and it does not require expensive transportation equipment to set up a grave. Whether the supports 46 or 47 are used, or whether a lowering device is used, the casket is placed in position either on the supports 46 or 47, or on the straps 62 on a lowering device, and the casket lid, of course, is removed and the two sections of the grave set are slid together, and are disposed on top of the casket box. This results in the draperies falling down and covering entirely the grave, and furthermore, the casket box just about fills the top of the grave, and prevents caving in of the grave, reduces the necessity of having to put grass mats inside the grave as where a conventional lowering device is used, and even when a conventional lowering device is used, the draperies of my improved grave set completely cover the lowering device, and also causes the relatives and others who may be adjacent the grave from stepping into the space between the casket box and the grave, and especially since with the use of the supports 46 and 47, the casket box is lowered into the grave, thus making it impossible for anyone to step into the open grave and thus injuring himself.

In the end elevations of the grave set and casket in Figure 6, it is noted that the rollers are somewhat shorter than those shown in Figure 3, it being evident that any desired length of roller can be employed, and also any desired number of these rollers can be employed. I show only five rollers on the grave set, but it is evident that any suitable number of additional rollers can be used as might be desired.

When this grave set is used with a conventional lowering device, the casket box is placed on the straps of the lowering device, and the top of the casket box is removed and then by use of the conventional lowering device, the box is let down into the grave six to ten inches, and by doing this, the box blocks the grave and keeps anyone from stepping into the space between the casket box and the edge of the grave, and it also prevents water from getting into the casket box, as here-

tofore this casket box has been lowered into the grave first, and then the casket is supported on the lowering device. With the casket box in lowered position, the grave set comprising sections 10 and 11 is placed over the open top of the box, and the drapery on the sides let down which completely covers the casket box, the lowering device, and completely hiding the whole grave from view. The pallbearers then place the casket on the first roller 42 of the grave set, and the casket is rolled onto the grave set, the adjustable rollers 31 serving to prevent the casket from rolling off of the grave set either endwise or laterally.

After the grave service is over, the casket is lifted a few inches, and two attendants, one at each end of the grave set remove the sections 10 and 11 from the grave set, and the casket is lowered into the casket box by hand or short straps, and the casket box top is put on and screwed into position, and after the top is secured, the box is lowered into the grave.

If desired, the grave set can be used without the use of lowering devices and without the use of the downwardly bent members 46 and 47 as plain boards or other means may be placed across the top of the grave for supporting the casket box, but it is preferable to lower it into the grave, for the above-specified reasons.

In the drawings and specification, there has

been set forth a preferred embodiment of the invention and although specific terms are employed, they are used in a generic and descriptive sense only and not for purposes of limitation, the scope of the invention being defined in the claim.

I claim:

In a grave set, a board-like member adapted to rest on top of a casket box, vault, and the like disposed above an open grave, said board-like member having a plurality of rollers on its upper surface for supporting a casket, a pair of vertically disposed and laterally adjustable guide members disposed adjacent each side edge of the member, a vertically disposed and longitudinally adjustable guide member disposed adjacent one end of the member for limiting endwise movement of the casket on said member, said board-like member being severed transversely near its center to form two sections, a pair of laterally spaced and longitudinally extending strips secured to the lower surface of the two sections and having their proximate ends abutting against each other, the strips on one section having cavities in their ends adjacent the other section and the strips on the other section having projections extending therefrom adapted to fit into the cavities in the ends of the first-named strips.

ROBERT Y. WOLFE.
